UNITED STATES PATENT OFFICE.

GIUSEPPE VITULLI MONTARULI, OF ROME, ITALY.

CONSTRUCTION OF SHIPS.

1,346,760.

Specification of Letters Patent. Patented July 13, 1920.

Application filed October 16, 1918. Serial No. 258,324.

To all whom it may concern:

Be it known that I, GIUSEPPE VITULLI MONTARULI, a subject of the King of Italy, and residing at 29 via Brescia, Rome, Italy, have invented certain new and useful Improvements in the Construction of Ships, of which the following is a specification.

The object of this invention is to design and construct hulls of a new geometrical shape for ships of any type and for any traffic.

This new geometrical shape of the hull comprises at the center a cylindrical portion of almost elliptical cross section and 15 tapered fore and aft end portions which extend onward from the terminal sections of the cylindrical portion along gradually narrowed or flute beak sections and end in a straight line section along the bow and 20 the stern.

The essential feature of the invention is the geometrical shape of hulls constructed in accordance with this new method of ship construction and same is illustrated by way 25 of example in the accompanying drawing, in which—

Figure 1 shows on the left-hand side, in 1, the midship section of the hull and on the right-hand side, in 2, the curvature of 30 this section,

Fig. 2 shows the hull divided into three parts 3, 4 and 5 of different geometrical shape,

Fig. 3 shows in horizontal position and 35 Figs. 4 and 5 show in projections of vertical sections the shape of the hull forward and aft in accordance with the invention.

In Fig. 1, the curve portion ABC is a circular arc which has its center at D and 40 connects at its ends A and C with other circular arcs AE and CF whose centers are respectively in G and H, so that these circular arcs set up the curve EABCF which consists of circular segments arranged to 45 form half a section of the central part 3 on Fig. 2 of the hull. The hull will thus have at its center part a cylindrical shape of constant section.

The forward end 4 (Fig. 2) is built up 50 from section 6 of midship section onward with the aid of sections 7, 8, 9, 10 and 11

which consists of circular arcs above and below and of straight lines at the center part, until they reach the forward end 12 with an entirely rectilinear section.

55

The sections of the after end 5 (Fig. 2) are similar to those of the forward end and they extend onward from the last section 13 of the cylindrical or elliptical portion so as to reach gradually along sections 14, 15, 16, 17 and 18 the rectilinear stern section 19, the only difference between the forward and after end portions being that the latter is tapered below so as to leave there a free space for the working of the screws.

65

The shape of the hull built up in the above described manner allows its main parts being constructed with interchangeable elements of constant curvature, whereby a standardization of the construction is attained for building ships in series.

70

As regards the central cylindrical portion of the ship this construction is shown schematically in 1 on the left-hand side of Fig. 1. In this central part the section of the 75 hull consists substantially of a frame 20 which may have the section of any ordinary bar used in shipbuilding, and of layers of plates to form the outer plating 21.

A double bottom 22 may have any desired 80 shape, and 23 is a hatchway and 24 a section of the deck in correspondence with the hatchways.

What I claim is:

A ship having a plurality of transverse 85 frames, the frames for a determinate length of the ship being formed with side sections of constant curvature and top and bottom curved sections having radii approximately twice the length of the radii of said side 90 sections, the remaining portion of the ship having similar frames with straight portions at the sides of gradually increasing length.

In testimony whereof I have signed my 95 name in the presence of two subscribing witnesses the 21 day of August, 1918.

GIUSEPPE VITULLI MONTARULI.

Witnesses:

IVAN LAIRETSKY,
NICOLO PATEMILLI.
